UNITED STATES PATENT OFFICE.

URIAH S. JACKSON, OF OSSYPEE, NEW HAMPSHIRE, ASSIGNOR TO THE SUPERIOR AUTOMATIC TELEPHONE COMPANY, OF BOSTON, MASSACHUSETTS, A CORPORATION OF MAINE.

TELEPHONE-SERVICE APPARATUS.

SPECIFICATION forming part of Letters Patent No. 750,769, dated January 26, 1904.

Application filed May 31, 1902. Serial No. 109,796. (No model.)

To all whom it may concern:

Be it known that I, URIAH S. JACKSON, of Ossipee, in the county of Carroll and State of New Hampshire, have invented a new and 5 useful Improvement in Telephone-Service Apparatus, of which the following, taken in connection with the accompanying drawings, is a specification.

My invention relates to a telephone-service apparatus so constructed and arranged that 10 any user in the group with which the service is connected may call up any other one of the group and at the same time cut off all others.

The exact arrangement and construction of 15 the apparatus and system may be best understood by reference to the full description and drawings.

The several figures constituting the drawings are as follows:

20 Figure 1 shows the outside of the box in elevation. Fig. 2 shows the box in elevation, the door being open. A part of the dial is represented as broken away. Fig. 3 shows the principal parts in elevation. Fig. 4 is a 25 vertical section showing the interior parts. Fig. 5 shows a detail. Fig. 6 is a diagram illustrating the method of connection with the source of electricity.

The outside case or box of my instrument is 30 indicated by A. A door B is hinged to the case and is shown as closed in Fig. 1 and as open in Fig. 2. There are as many of these boxes as there are users in the system. Each user has a number. In the present system 35 there are fourteen of these boxes, each of which is indicated by a numeral on the dial D, Figs. 1 and 2. A pointer D' moves on the dial and is made to indicate to the user that the desired or "called" box is in connection 40 and may be communicated with.

The mechanisms by which the calls are made may be described as follows: The lever L is rigidly connected to a shaft L², and the said shaft L² has fixed upon it a drum L⁷ and a 45 notched wheel L⁴, as shown in Fig. 4. A coiled spring S, as indicated in dotted lines, has one end attached to the drum L⁷ and the other end to the post a on the plate A'. A

pawl L⁵ is pivoted to the spur-gear L⁶ and is adapted to engage with the notched wheel L⁴, 50 thus admitting this notched wheel to be turned by the depressing-lever L in the direction of the arrow without turning the spur-gear L⁶. This action of turning the notched wheel L⁴, and with it the drum L⁷, winds up the spring, 55 and as one end of the said spring is attached to the drum L⁷ it is evident that the reaction of the said spring will give motion to the spur-gear L⁶ in a direction opposite to that indicated by the arrow. This action will take 60 place whenever the lever L is depressed. The lever is returned to its normal or elevated position by the movement of the spur-gear L⁶, acting through the pawl L⁵, notched wheel L⁴, 65 drum L⁷, and shaft L².

The spur-gear L⁶ communicates motion to the pinion T and the shaft C', thence to the contact make-and-break wheel C². (See Figs. 4 and 5.) The train T', T², T³, and T⁴ and the escapement T⁵ have no function except to prevent the make-and-break wheel C² from rotating too rapidly. The number of points C³ on the wheel C² are equal to the numbers on the dial D and to the number of boxes in the system. The pin C⁴ in the make-and-break 75 wheel C², Figs. 3 and 5, extends through said wheel and serves two purposes. Thus the part C⁴ above the wheel serves as a stop for the wheel when it comes in contact with the stop-key C⁶, which may be inserted in any 80 one of the holes, numbered from one to fourteen, on the stationary disk C. Thus the said make-and-break wheel may be made to stop after having made the desired number of contacts with the electrodes G and G', as will be 85 explained hereinafter. The part C⁶ below said make-and-break wheel serves to stop the said wheel by coming in contact with the end L' of the lever L when the said lever is in its normal or resting position, as indicated in 90 Fig. 2—that is, the wheel is stopped when it has made a complete rotation and has brought the pointer D' to "0" on the dial D, as will be explained. The lever L has upon it a pin L³, which is arranged to engage with the hook 95 L⁹ on the bell-crank lever L¹⁰ L¹¹, (pivoted at

L^{12} .) This lever $L^{10} L^{11}$ is thrown into its locking position, as shown in Fig. 3, by the spring L^{13} and holds the operating or winding-up lever L in the position indicated by dotted lines, so that the said winding-up lever L cannot be used except when the cam-boss L^8 on the pinion D^3 is in the position shown in dotted lines in Fig. 2, at which position the pointer-hand D' is at "0" on the fixed dial.

The above-described movements are dependent upon the action of the coil-spring S , which is attached to the drum L^7 and the spur gear-wheel L^6 and relate to the operation of the electric make-and-break electrodes G and G' . (See Fig. 3.)

I will now describe the electrical device that operates the pointer-hand D' on the fixed dial D . An electromagnet $M M$ is energized by an electric current passing through the wire m , electrodes $G G'$, and the wires $m' m^2$, Fig. 3. An armature M' is pivoted at M^2 and has attached to it a double-acting pawl M^3 . The action of the magnet when energized is to swing the double pawl M^3 in one direction and that of the spring M^4 (when the magnet is not energized) to swing the said pawl in the other direction, and this back and forth motion of the double pawl M^3 serves to give an intermittent rotary motion to the trunnion-pinion D^3 . The trunnions of this pinion are indicated by $D^4 D^4$. The pointer-hand D' is attached to the shaft D^2 of the pinion D^3 , so that a forth and back motion of the double pawl M^3 will cause the pointer-hand D' to move one division on the fixed dial D —that is, the forth and back completed motion of the said double pawl will cause the pointer-hand to move from "0" to "1" and the next from "1" to "2," and so on.

The telephone-circuit is indicated by the wires $n n'$, which are respectively connected to the spring-electrodes H' and H^2 . When the contact-points of the electrodes are together, as indicated in Fig. 3, then the desired telephone-box may be called; but when these contact-points are not together no telephone can be called. There are two devices for closing the circuit through the electrodes. The first consists of the bent lever $N N^2$, (pivoted at N' .) The upper end N^2 of this lever rests against the spring-electrode H' and will hold the said spring-electrode in contact with the other electrode H^2 for the reason that the bent lever $N N^2$ has a strong spring N^3 , which will force the end N^2 upward, and thus keep the contact-point of the electrode H' against the corresponding point of the electrode H^2 , thus keeping the telephone-circuit closed and ready for use; but when the lever L is in its raised or normal resting position then the pin L^3 presses against the lower arm N of the lever $N N^2$, and thus causes the upper arm N^2 to be depressed, thus allowing the electrode H' to break contact. (See Fig. 2.) The other de-

vice for closing the electrodes $H' H^2$ consists of a pin H on the pinion D^3 . (See Fig. 2.) This pin is so located that when the pointer-hand D' is on the number that indicates the number of the box in which it is placed then the telephone-circuit is closed and the telephone of this box can be used. The location of the pin H on the pinion is different for each box. For instance, in box No. 1 the pin H is so placed that when No. 1 is called, it, the pin, will close the telephone-circuit when the hand is on No. 1, and in box No. 6 the pin is so placed that it will close the telephone-circuit when the hand is on No. 6 of the dial, and so on.

The operation of my telephone apparatus is as follows: Suppose that No. 1 wishes to call No. 6. He puts the stop-key C^6 into the hole No. 6 in the disk C . Then he depresses the lever L . (The levers L of all the boxes are free when the pointer-hand is on "0.") That action at once frees the lower end of the bent lever $N N^2$ and allows the spring N^3 to throw the end N^2 upward, thus closing the circuit through the telephone-electrodes $H' H^2$ and thence the telephone-circuit itself. A continued depression of the lever winds up the actuating-spring and causes the notched contact-wheel C^2 to rotate. This wheel will continue to rotate until the pin C^4 on it comes in contact with the stop-key C^6 —that is, until six of the points C^3 of the notched wheel C^2 have come in contact with the electrode G' six times—thus making six breaks and contacts, and as each make and break, acting through the circuit $m m' m^2$, (see Figs. 3 and 6,) will charge and discharge the magnet M it follows that the double-pawl lever M^3 will have operated in all the boxes and set all of the trunnion-pinions D^3 ahead six numbers. This action will cause the pin H of box No. 6 to close the telephone-circuit for that box and enable No. 1 to communicate with No. 6, as desired. It will be noticed that although all of the levers L of the boxes are free when none are in use as soon as a lever in any one box is depressed it will start the pinions D^3 of all of the boxes, which will cause the boss L^8 to move from under the end L^1 of the lever $L^{10} L^{11}$, and thus allow them to hook onto their respective pins L^3 and at once lock all of the levers L .

An enumerator, as E , may be placed at any convenient point. A stop-pin h serves to limit the motion of both the lever $L^{10} L^{11}$ and the lever $N N^2$.

To restore the apparatus to its normal condition, the user withdraws the stop-key C^6 from the hole in the disk C . This action allows the movements of the several parts to continue until the pin C^4 on the notched contact-wheel C^2 comes in contact with the end L^1 of the lever L^8 and the pointer-hand is on "0."

I claim—

1. In a telephone-service apparatus: a pin-

ion-wheel adapted to receive a step-by-step rotating motion: means for producing said motion: a pointer on said wheel adapted to indicate on a dial a box-number, as described: a 5 cam-boss on said pinion; a locking bell-crank lever having a hook upon one end, and arranged to be operated by said cam-boss; and a winding-up lever having a pin, with which the said hook engages and thereby locks the 10 said winding-up lever, substantially as and for the purpose set forth.

2. In a telephone-service apparatus: a clock-train; a hand-lever adapted to give motive energy to the said clock-train; an electrical circuit; a spring-actuated bent lever constructed to close said electrical circuit; and a pin on said hand-lever adapted to hold back the said spring-actuated bent lever when said hand-lever is up, and to release said spring-actuated 15 20 bent lever when depressed, whereby said circuit

is closed, substantially as and for the purpose set forth.

3. In a telephone-service apparatus: an electric telephone-circuit: a pinion-wheel adapted to receive a step-by-step rotating motion: 25 means for producing said motion: a pin, *h*, on said wheel constructed to close the said telephone-circuit: a boss, *L*⁸, on said wheel: a bent lever *L*¹⁰ *L*¹¹ acted upon by said boss and constructed to lock a winding-up lever, 30 and said winding-up lever substantially as and for the purpose set forth.

In testimony whereof I have signed my name to this specification, in the presence of two subscribing witnesses, on this 28th day of May, 35 A. D. 1902.

URIAH S. JACKSON.
